R. C. STRIKER

GAME DEVICE

Filed Oct. 29, 1921

23-6 Inventor
Robert Calder Straker
By John Attorney

of George H. Sande

UNITED STATES PATENT OFFICE.

ROBERT CALDER STRIKER, OF BROOKLYN, NEW YORK.

GAME DEVICE.

Application filed October 29, 1921. Serial No. 511,396.

To all whom it may concern:

Be it known that I, ROBERT CALDER STRIKER, a citizen of the United States, residing at Brooklyn, in the county of Kings 5 and State of New York, have invented certain new and useful Improvements in Game Devices, of which the following is a specification.

This invention relates to a game device. 10 An object of the invention is to provide a game device particularly adapted for use at fairs, bazars, so-called side shows and the like, and to make the device of unique and attractive appearance.

15 A further object is to so design the parts of the device that they may be readily assembled and disassembled and thereby adapted for easy transportation.

20 A further object is to so design the device that its operation will be suitably mystifying and amusing to compel attention.

Other objects and aims of the invention, more or less specific than those referred to above, will be in part obvious and in part 25 pointed out in the course of the following description of the elements, combinations, arrangements of parts and applications of principles, constituting the invention, and the scope of protection contemplated will 30 be indicated in the appended claim.

In the accompanying drawings which are to be taken as a part of this specification, and in which I have shown merely a preferred form of embodiment of the invention:—

Figure 1 is a front elevational view of a device constructed in accordance with this invention.

40 Figure 2 is a side elevational view of the structure seen in Fig. 1, parts of the device being shown in vertical central section.

Figure 3 is a top plan view of the rotor element employed, portions being broken away and illustrated in section for better 45 disclosing details of construction.

Figure 4 is an enlarged fragmentary detail view in vertical section showing the manner of constructing the rotor element, and

50 Figure 5 is a fragmentary detail view of a portion of the supporting frame and illustrating the manner of detachably mounting the top member of the frame.

Referring to the drawings for describing 55 in detail the structure therein illustrated, the reference character L indicates a base

from which rises a pair of standards 1 and 2. These standards are connected together at their opposite ends by a top piece 3.

The base, standards and top piece constitute a suitable frame for containing a supporting rotor G mounted to rotate freely upon a vertical axis.

The rotor G may be of any suitable shape or construction but preferably is shaped 65 and constructed as indicated; that is, it is made to represent an ordinary wooden top of the type such as is commonly used as a plaything by young boys, as will be appreciated by inspection of the drawings, being 70 relatively broad and rounded at its upper portion and tapering downwardly to a point. A suitable part, as 4, is provided at the lower end to represent the well known “plug” present in tops of this character. 75

Extending preferably around the breast part, or largest circumference, of the top is a series of numbers or other indicating marks H, and carried preferably by the top piece 3 is a stationary pointer 5 adapted 80 for directing attention to, or selecting, one of the marks H as such mark comes to rest beneath the pointer whenever the rotor has ceased rotation.

The pointer, or selecting device, 5 has no 85 connection, nor does it in any way interfere with the rotation of the rotor, and here it may be noted that an essential characteristic of this device resides in the fact that the rotor is mounted to rotate upon a vertical axis, that its weight is supported upon a single point at its lower end, and that it is of suitable size and weight so that even the rotating very slowly the period of rotation will continue for an unexpectedly 90 long period.

The speed of rotation of the rotor may be so slow that the indicating marks H can be at all times readily discernible and spectators will be mystified and astonished to see 100 one mark after the other pass the pointer when they imagined each would be the last. Much amusement is thus had and interest created certain to increase the crowd of spectators.

105 A brief explanation of the manner of using this device may now be given as follows:—

Each of a crowd of spectators selects one of the numbers, or identifying marks H of 110 the rotor. An attendant will now manually rotate the rotor and the spectator who is

fortunate enough to have selected as his own the number which is indicated by the pointer 5 when the rotor comes to rest is declared winner.

5 It will be seen thus that much amusement and excitement will be created amongst the spectators as the numbers move slowly past the pointer.

10 The lower, or supporting, pivot for the rotor consists of a small cone, as 6, resting in a cone bearing which is provided to receive it in a wear plate 7 carried by the base L.

15 The upper pivot, intended only to maintain the rotor in a proper vertical position, may consist of a stud 8 projecting vertically above the upper end of the rotor and engaging within a suitable wear plate 9 carried by the top piece 3.

20 Any suitable provision may be made for the ready assembly and disassembly of the various parts of this device. By way of suggestion the drawing illustrates for this purpose a construction as follows:

25 The rotor is made up of a plurality of segments, as 10, 11, 12 and 13, extending vertically thereof, the lower ends of the segments being received in a suitable pocket provided within a band 14 at the lower, or 30 "plug" end and are held together at their upper ends by a cap piece 15 having an annular flange which engages studs 17, 18, 19 and 20, carried respectively by the several segments.

35 As seen particularly in Fig. 4, the pivot cone 6, and the pivot stud 8, are connected together, and in fact are integral parts of a single tie rod 21 which extends vertically thru the rotor, the cone 6 constituting a 40 head at the lower end of said rod and the stud 8 being preferably a reduced extension at the upper end of said rod. Just below the stud 8 the rod is threaded and carries a nut 22 which appears upon the upper 45 surface of the cap piece 15 and serves to hold said cap piece in snug engagement with the studs 17.

The band 14, which, to all outward appearance constitutes the "plug" of the top, 50 surrounds a core piece 23 to which it is rigidly connected, the upper annular edge of the band projecting above the top surface of the core so as to provide the pocket, or depression, into which the lower ends of the 55 segments 10-13 extend. This core has an opening 24 thru its center to accommodate the rod 21.

At any selected intermediate point, or points, the segments may be connected together by suitable clamp, or other retaining devices, as indicated by the reference numerals 25 and 26, the device 25 being suitable for use interiorly of the rotor and the device 26 for use exteriorly of the rotor. 65 The standards, or frame pieces, 1 and 2

may be separably connected with the base L by being provided with downwardly extending portions 27 for entering sockets 28 provided to receive them in the base.

70 The top piece 3 may be connected with the standards 1 and 2, for instance, by being provided with plates, as 29, at its opposite ends, said plates having key slots, as 30, for interengagement with headed studs 31 projecting from the standards, as seen in Fig. 5.

75 The pointer 5 may consist of a single piece of metal properly shaped and having a threaded extension 32 continuing beyond a suitable shoulder 33 and adapted to carry 80 a nut 34 by which the pointer may be locked in position extending thru a suitable opening provided for the purpose transversely of the top piece 3.

85 By this construction it will be seen that altho the several parts may be readily shipped in knocked down condition, yet they may be readily assembled when desired for use. After the rotor has been assembled, and the standards 1 and 2 placed 90 in position upon the base, the rotor is placed with its cone point 6 resting in the cone bearing of the plate 7, and the top piece 3 is then slipped into position engaging the stud 8, whereupon the device is ready 95 for use.

90 The device 25 may constitute weights, or the rotor may be otherwise weighted, if desired, for increasing the precision of its movements.

100 Having thus described my invention, what I claim as new and desire to secure by Letters Patent is:

A game device of the type indicated comprising: a top-shaped rotor having upper and lower pivot parts in the plane of the longitudinal central axis of the rotor, a support for the rotor having a lower bearing part with which the lower pivot part engages to directly support the weight of the 11 rotor, said support comprising a frame extending upwardly and across the top of the rotor having an upper bearing part with which the upper pivot part of the rotor engages to retain the rotor in a vertical 12 position adapted to rotate about a vertical axis, indications carried by the rotor spaced apart in a row extending around its circumference, and a pointer fixed to the upper cross member of the frame and extending radially across the top of the rotor and thence vertically downwardly to the horizontal plane of said row of indications, for use in the manner set forth.

120 In testimony whereof I affix my signature in the presence of two witnesses.

ROBERT CALDER STRIKER.
